UNITED STATES PATENT OFFICE

JAMES G. RAMSEY, OF WILMINGTON, DELAWARE, ASSIGNOR TO THE JESSUP & MOORE PAPER CO., OF PHILADELPHIA, PENNSYLVANIA, A CORPORATION OF MASSACHUSETTS

METHOD OF AND APPARATUS FOR STOCK MANIPULATION

Application filed December 20, 1928. Serial No. 327,359.

This invention relates to a method of and apparatus for feeding or flowing stock to a refining engine or Fourdrinier wire, or both.

The particular object of the invention is the feeding of stock in such a way as to effect a suspension in order that a perfect web may be made upon withdrawal of the suspending medium.

It is well known in this art that the raw materials which go to make up the paper must be thoroughly mixed and carded in a dilute suspension so that the stock may be formed into a homogeneous web which will be uniform and free from lumps and clots. The beating and refining must necessarily take place in a liquid suspension which is fairly thick, usually 4 to 5 parts of raw material, to make up to 100 parts. This suspension must then be thinned to about one-half of one part of raw materials to make 100 parts to effect a further suspension, and before it can be made to screen and knit together properly to form a web on the Fourdrinier wire. It is, therefore, necessary that a very large volume of water be supplied to dilute the thick stock which is being continuously pumped from the refining engine to the paper machines to be screened, and to be thereafter separated from the suspending water on the Fourdrinier wire.

A great deal of difficulty has been experienced in eliminating imperfections in the web. Many of these imperfections are due to the fact that it is practically impossible to supply stock from the refining machines under a constant flow, and free from lumps and bubbles. The invention is, therefore, concerned with the elimination of lumps, froth and foam spots and the production of a sheet in which the regulation of weight or thickness is expeditiously controlled.

To this end the invention consists in the provision of a stock box divided into several compartments, one of which is provided with an adjustable measuring gate or wier, the stock being supplied to that compartment faster than it can flow out of the gate to the refining machine. Means are provided to take care of the overflow from

this compartment. Operating on this principle, stock is supplied both to the Jordan and the Fourdrinier under a constant hydrostatic head, with the result that the flow is absolutely constant as compared with the usual fluctuations of pump pressure.

The invention further consists in the novel arrangement, combination and construction of parts more fully described hereinafter and shown in the accompanying drawings.

In the drawings:

Fig. 1 is a side elevation partly in section, showing an embodiment of my invention.

Fig. 2 is a plan view of the arrangement of Fig. 1.

Fig. 3 is a sectional elevation view along the line 3—3 of Fig. 2.

Fig. 4 is a sectional view along the line 4—4 of Fig. 2.

Referring now with particularity to the embodiment illustrated, I have shown at 1 a box for beaten stock which consists of several compartments. Into a section, which I shall term the inflow compartment 2, is arranged an intake or supply pipe 3 through which stock enters from the beater chest. A partition 4 between the longitudinal walls of the box 1 but lower than the end walls thereof, is provided, over which spills the stock inflowing through the pipe 3. A similar wall 5, and of substantially the same height as the wall 4, forms therebetween what I shall term an outflow compartment 6. This compartment is provided with an aperture 7 closed by an adjustable gate 8 in the usual manner. This gate, therefore, is used to regulate the amount of stock leaving the outflow compartment 6.

Between the wall 5 and the end wall 9 of the box 1 is an overflow compartment 10 provided with an overflow pipe 11.

The stock flowing out of the aperture 7 enters the measuring box 12 and flows by means of the outlet pipe 13 to a refining engine of any desired type, and which is not here illustrated.

In operation the stock from the beater chest will be supplied through the pipe 3 to the inflow compartment 2 faster than it can flow out of the aperture 7 into the neighbor-

ing or intermediate compartment. Obviously the stock reaches this compartment by flowing over the top of the wall 4. Due to this method of feeding the stock, the compartment 6 will soon fill to the top and the excess will overflow into the compartment 10 and out through the pipe 11 back to the supply for beaten stock. Thus, the stock flowing out of the aperture 7 to the refining engine 10 does so under a constant hydrostatic head and does not depend upon a pump, thereby eliminating the usual fluctuations occurring through the use of such a device.

The fact that the beaten stock has to pass through compartments 2, 6 and 12, as well as pipe 13, before reaching the refining engine, permits any froth or bubbles existing therein to become dissipated, which thus adds to the uniformity of the final web.

20 This same principle is applied to the device used for further diluting the refined stock and flowing the same to the Fourdrinier and intermediate screens.

25 Such a device may be embodied in a box having a compartment 14 therein into which white water is supplied through the pipe 15. Suitable baffles 16 are located above the pipe 15 to prevent undue splashing.

30 Within the compartment 14 I provide an overflow pipe 16', preferably rectangular in cross-section in order to prevent swirling, the top being at a level above the outlet 17 for the white water. The outlet 17 may also be provided with an adjustable gate 18 so that 35 the size of the opening may be controlled. As before, it is desirable to supply white water to the box 14 faster than this diluting water can flow through the outlet 17. Such being the case, the excess will flow into the 40 top of the overflow pipe 16' and from there to the wire pit.

45 At the front of the box 14 I provide a mixing box 19 into which the refined stock from the Jordan or other refining engine is supplied, as above set out. The diluting water flowing through the outlet 17 is also discharged into this box.

50 The side walls 20 of this mixing box overlap in spaced relation the extension 21 of the side walls of the box 14. This causes the thus diluted stock to travel a circuitous path and spill over the top of the wall 20 into the side or screen boxes 22 to reach the openings 23 from which the diluted refined stock 55 flows to the Fourdrinier.

60 It will thus be seen that by such an arrangement, the diluted water is supplied under a constant hydrostatic head due to the 65 fact that the inflow through pipe 15 is greater than the outflow through the opening 17, and inasmuch as the height of the overflow pipe 16' is above the outlet 17. This constant supply of diluting water is mixed in the box 19 with a similarly constant supply of re-

fined stock so that the Fourdrinier receives an unfluctuating supply of material.

It is essential that a constant level for both stock and water be maintained in order to produce efficient results.

I claim:

1. A method of feeding stock to a Fourdrinier wire, which includes the steps of maintaining a constant head of stock from a beater to a Jordan, maintaining a constant head of refined stock from the Jordan to a mixing box, maintaining a constant head of diluting water, flowing the diluting water into the mixing box for the refined stock, and flowing the diluted stock to a Fourdrinier.

75 2. A method of feeding stock to a Fourdrinier wire, which includes the steps of flowing diluting water under a constant hydrostatic head into a mixing box, flowing refined stock under a constant hydrostatic head, also to said box, and flowing the thus diluted refined stock to a Fourdrinier.

80 3. A method of feeding stock to a Fourdrinier wire, which consists of flowing refined stock into a mixing box, supplying diluting water to a compartment, and flowing said diluting water into said mixing box from said compartment, the water being supplied to the compartment faster than it can flow into the mixing box, and overflowing the excess water 90 at a point higher than the outlet into the mixing box, and flowing the thus diluted stock to the Fourdrinier.

95 4. A beater stock box having an inflow compartment into which stock from a beater chest is supplied, an outflow compartment having an outlet gate therein, said outflow compartment receiving stock from the inflow compartment, an overflow compartment receiving stock from the outflow compartment, a take-off pipe for the overflow compartment and means to supply beater stock to the inflow compartment faster than the stock can pass through the outlet gate of the outflow compartment.

100 5. In combination, a mixing and measuring box including a mixing compartment, means to supply refined stock thereto, a diluting water compartment, a gate between the two compartments, means to supply the water compartment with a greater supply of water than can flow out of said gate into said mixing compartment, an overflow outlet for the water compartment, spaced walls extending from the water compartment on either side 115 of the water gate and over the mixing compartment, the lower ends of said walls being above the bottom of the mixing compartment, the bottom of the mixing compartment being below the bottom of the water compartment, said mixing compartment having side walls between and overlapping said extending walls in spaced relation, and screen boxes one at either side of the said mixing compartment, having outlets to the Four- 120 drinier.

drinier whereby the diluted refined stock is caused to travel a circuitous path in passing over the side walls of the mixing box into the screen boxes and thence to the Four-
5 drinier in unfluctuating supply.

6. In combination, a beater stock box de-
livering stock under a constant head to a
Jordan, said Jordan delivering a constant
10 flow of refined stock to a mixing box, means
delivering a constant head of diluting water
to said mixing box, said mixing box deliver-
ing a constant flow of diluted refined stock to
a Fourdrinier.

7. Apparatus according to claim 6, in
15 which said beater stock box has an inflow
compartment, an outflow compartment with
a gate in its wall to supply a Jordan, an
overflow compartment receiving overflow
stock from the top of the outflow comp-
20 partment, and means to supply stock to the inflow
compartment faster than the stock can pass
through the outlet gate of the outflow com-
partment.

8. Apparatus according to claim 6 in
25 which said beater stock box has an inflow
compartment, an outflow compartment with
a gate in its wall to supply a Jordan, an
overflow compartment receiving overflow
stock from the top of the outflow comp-
30 partment, and means to supply stock to the inflow
compartment faster than the stock can pass
through the outlet gate of the outflow com-
partment, said means for delivering a con-
stant head of diluting water to said mixing
35 box comprising a diluting water compart-
ment providing a gate between the water com-
partment and mixing box, means to supply
the water compartment with a greater supply
of water than can flow out of said gate into
40 said mixing box, and an overflow outlet for
the diluting water compartment.

9. Apparatus according to claim 6, in
45 which said beater stock box has an inflow
compartment, an outflow compartment with
a gate in its wall to supply a Jordan, an
overflow compartment receiving overflow
stock from the top of the outflow comp-
50 partment, and means to supply stock to the
inflow compartment faster than the stock can
pass through the outlet gate of the outflow
compartment, said beater stock box having a
measuring compartment disposed to receive
55 the stock from the outlet gate, the bottom of
said measuring compartment being below the
level of the bottom of the outflow com-
partment.

10. Apparatus according to claim 6, in
60 which said beater stock box has an inflow
compartment, an outflow compartment with
a gate in its wall to supply a Jordan, an
overflow compartment receiving overflow
stock from the top of the outflow comp-
65 partment, and means to supply stock to the
inflow compartment faster than the stock can
pass through the outlet gate of the outflow

compartment, said means for delivering a
constant head of diluting water to said mix-
ing box comprising a diluting water compart-
ment providing a gate between the water com-
partment and mixing box, means to supply 70
the water compartment with a greater sup-
ply of water than can flow out of said gate
into said mixing box, and an overflow out-
let for the diluting water compartment, said
overflow outlet comprising a vertical over- 75
flow pipe having its upper end above the
gate, said pipe being of rectangular cross-
section to prevent swirling.

In testimony whereof I affix my signature.
